CIGARETTE HOLDER

Willie A. Olson, Port Angeles, Wash.

Application August 2, 1943, Serial No. 496,979

5 Claims. (Cl. 131—175)

My invention relates to a lighted cigarette concealing holder. More particularly, my invention relates to a cigarette holder which permits lighting the cigarette in a light concealing housing, keeping the flash (upon lighting) concealed as well as the glow of the cigarette during smoking and providing for air circulation so that the cigarette will continue lighted when smoking is temporarily interrupted.

This device has particular utility aboard ship or on fighting fronts and in areas during wartime when dim out or black out regulations obtain, in forestry areas during dry seasons, around manufacturing plants or other places where a fire hazard obtains, or when smoking in rainy or windy weather. This device is designed to prevent any light showing when lighting or smoking and the escape of ashes, and to protect the cigarette when smoked in rainy or windy weather.

Difficulties obtain with prior art devices in that they do not provide for completely concealing the lighting of the cigarette and also in that they do not provide for keeping the cigarette lighted while smoking is temporarily interrupted.

A primary object of my invention is to provide a holder which permits striking a match within the holder while the burning portion of the match is completely concealed against any flash which accompanies the striking and which wipes out all lighted glow of the match head portion upon withdrawing the match from the housing or casing after lighting the cigarette.

Also it is my purpose to provide a holder which provides for maintaining a cigarette in lighted condition when smoking is temporarily interrupted.

Further it is an object of my invention to permit closing up the device when a cigarette is partially smoked and thereby promptly extinguish it so that it may be placed in a coat or vest pocket without danger of the ashes escaping. Thus the partially smoked cigarette will be preserved for relighting and the smoking thereof resumed at a subsequent time if desired.

Also it is an object of my invention to provide a holder in which cigarettes of different length may be smoked. Obviously, the device may be adapted for cigars in place of cigarettes.

The above mentioned general objects of my invention, together with others inherent in the same, are attained by the mechanism illustrated in the following drawing, the same being preferred exemplary forms of embodiment of my

invention, throughout which drawing like reference numerals indicate like parts:

Figure 1 is a plan view of a holder embodying my invention;

Fig. 2 is a view in vertical longitudinal section on line 2—2 of Fig. 1 with a cigarette in position;

Fig. 3 is a view in side elevation of the holder of my invention in disassembled or exploded position;

Fig. 4 is a view in section taken substantially on broken line 4—4 of Fig. 2;

Fig. 5 is a fragmentary view in longitudinal section of the enveloping casing and associated mounting member taken on a different plane than Fig. 2 and showing certain passageways and openings in open position;

Fig. 6 is a view in perspective of a closing or cap member;

Fig. 7 is a fragmentary development view representing, in a flat plane, the relatively telescopic end portions of a casing and a closing cap with valve opening passageways and securing pin and bayonet slot means, the casing and closing cap being shown in relatively separated or exploded relation;

Fig. 8 is a fragmentary view partly in longitudinal section and partly in elevation of a modified form of my invention with slots disposed longitudinally and diagonally;

Fig. 9 is a view in section of a modified form of my invention with the slots transversely or tangentially disposed;

Fig. 10 is a view of a modified form of construction of the rotary valve openings and passageways;

Fig. 11 is a view of another modified form of construction of the rotary valve openings and passageways employing bent tubes;

Fig. 12 is a view of still another modified form of construction of the rotary valve openings and passageways formed by a split rotatable band; and

Fig. 13 is a view in cross section on line 13—13 of Fig. 12.

A mouth piece 20 may be slidably connected to a cigarette holder member 21, which in turn has adjustably mounted thereon a cigarette enveloping casing mounting member 22. The holder member 21 may have a recess 23 of such diameter as to receive a cigarette 33 therein. The mouth piece 20 is preferably provided with a cavity 24 and the cigarette holder member with the axially disposed opening 25 to provide a saliva trap, or filter receiving means, but such is not

essential. The mouth piece and the cigarette holder member may be a single integral unit.

The enveloping casing mounting member 22 has openings 26, Figs. 3, 5 and 7, and associated grooves or passageways 27 formed in the telescoping end portion 28. Also such mounting member 22 has securing means which may be a pin 29 engageable with casing 31 as will be hereinafter set forth, as well as a cigarette axially positioning member 30 which may be a short piece of wire transversely disposed in recess 30a. This member 30 contacts the cigarette intermediate its otherwise unsupported length and gives support in addition to that afforded by the recess 23 into which it is pressed.

The cigarette enveloping casing member 31 is operatively disposed upon the cigarette casing mounting member 22 and has a cavity 32 which preferably has concave sides to provide an air space as large as possible about the cigarette 33. On the mounting end, the casing has openings 34, registerable on turning with passageways 27 in mounting member 22 and a bayonet slot 35, see Fig. 7, to receive securing pin 29.

Fig. 7 shows the two cylindrical parts 28 and 31 as they would appear if they were spread out in a flat plane and separated a short distance apart. In the act of telescopically engaging these parts, the pin 29 will move along the longitudinal portion of the slot 35 until it is in line with the transverse portion of said slot 35 and the two parts 28 and 31 are completely telescoped as respects relative longitudinal movement. Parts 28 and 31 can then be relatively moved rotatively a distance limited by the length of the transverse portion of the slot to move the notches 34 into or out of registration with the grooves 27 and open or close the air passageways formed by openings 26, grooves 27 and notches 34. Obviously, parts 31 and 28 will be locked against disassembly when the air passageways are in either the fully open or the fully closed position.

In the cigarette lighting end portion a match inserting opening 36 is provided with an elastic covering 37 preferably of rubber, having an opening formed by a cut or closed slot 37a. In the wall of the casing opposite opening 36 is secured a match scratching element 38, preferably of file construction. This element is preferably located in close proximity to the end of the cigarette 33 and a corner 39 of the element is preferably provided in spaced relation to the end of the closing or cap member 40. This corner 39, I find, greatly facilitates the lighting of a match 41.

Casing member 31 has notches 42 in the end portion thereof that are adapted to register with longitudinally directed grooves or passageways 44 in cap 40, which passageways 44 in turn have offset openings 45 which lead to inside the casing, i. e., to recess 46 of cap 40. Pin 47 operating in bayonet slot 48 serves to hold cap 40 in place. The offset character of the openings prevents the direct showing of light from within.

In the modified form of the device shown in Fig. 8, a simplified embodiment of my invention is illustrated. The mouthpiece 49 serves also as the cigarette enveloping casing mounting member for cigarette enveloping casing member 50. Instead of offset slots to prevent the escape of light, longitudinally inclined slots 51 and 52 are provided in the walls of casing member 50.

At the end adjacent the lighted

site end. Slots of this inclined character will serve for protection against wind and rain and fire hazard, but will not conceal the light as completely as the offset openings, and where such concealment is the prime consideration then the offset type is preferred. While the slots 51 and 52 may be inclined opposite to the direction shown, and possibly, at least so far as slots 52 are concerned, serve to conceal the light better,

10 nevertheless the draft or circulation of air would not be so well provided. Hence, the slots, where the inclined type are employed, are preferably inclined in the direction as set forth. The end portion next to the lighted end of the cigarette 15 53 is formed integrally with casing 50, with scratching element 54, opening 55, and slotted elastic covering 56. The relatively offset openings shown in Figs. 1 to 7 will insure a more positive concealing of light within the casing but 20 the inclined slots 51 and 52 will be a more simple construction.

In Fig. 9, the slots 57 are tangentially or transversely disposed in casing 58 instead of longitudinally directed.

25 In Fig. 10 still another modified form of construction to provide relatively offset openings is shown. In cap 59, passageways or openings 60 are provided extending into the axial recess 62 of cap 59. On a shoulder 61 of cap 59 a cylindrical member 63 is mounted having openings 64. This member 63 is of lesser diameter than the recess 62 so that longitudinally directed annular passageway 64a is provided between the member 63 and the inner wall of the cap 59. 30 Thus openings 64 are offset with respect to openings 60 and this is accomplished by a simple construction. The cap 59 may be secured on the end portion of casing 66 in any suitable manner.

35 In Fig. 11 a further modified means for providing an offset passageway or opening from an internal cavity 67 to the outside of a casing 68 is shown. Herein bent tubes 69 are mounted in the walls of the casing 68.

40 In Figs. 12 and 13 still a further modified construction is shown wherein a ring 70 is revolvably mounted in an annular groove 71 in the casing 72. Casing 72 has recess 73 connected through openings 74 to passageways 75, formed in the inner wall of ring 70, to port 76. To close 45 the offset ports obviously it is only necessary to revolve the ring 70 through a small arc.

45 The mode of operation is as follows: The cigarette 33 is inserted in recess 23 of cigarette holder 21 and lined up axially by resting on member 30. Then cigarette enveloping casing member 31 is put in place on mounting member 22 by causing pin 29 to enter bayonet slot 35, and parts 31 and 22 are relatively turned until passageways 27 register with ports 34. Likewise openings or 50 ports 42 in the casing member 31 are brought into registration with passageways 44 of cap 40.

55 Since casing mounting member 22 is slidably disposed upon cigarette holding member 21, it is possible to adjust the holder to cigarettes of different length.

60 The wire means 30 functions to effectually maintain the cigarette in axial position. This facilitates lighting and also the circulation of air to keep the cigarette lighted for a period of minutes as hereinafter set forth when smoking of the cigarette is temporarily interrupted.

65 Then a match 41 is inserted through the cut 37a in the rubber covering 37 and through hole 38 and positioned with the head of the match on or in close proximity to the match scratching

element 38. The match is then moved preferably so that the match head strikes corner 39, whereupon it generally becomes lighted without moving further and then by drawing on mouthpiece 20, the cigarette is lighted. I find that this corner 39 is very helpful in causing the match to light. There is little space and as the scratching element is used, ashes accumulate. Lighting becomes particularly difficult, when the element becomes fouled. The corner 39 overcomes this difficulty, and provides for operating pending cleaning. As the match is withdrawn, the rubber covering wipes out any glowing portion and prevents any flash from being seen during the lighting and any light during smoking.

When it is desired to temporarily interrupt smoking for a few minutes, the device may be placed in the pocket with either end up, i. e., in substantially vertical position with the openings in open position. In such case the cigarette will remain lighted for a period of minutes, averaging from two to seven minutes. The openings in spaced relation to the lighted end of the cigarette, i. e., those as 34 near the mounting portion or butt end of the cigarette may serve to admit air to replace that which is heated by the lighted end portion of the cigarette and which escapes through the openings 42 and connected passageways when the holder is in upright position. Of course, with the position of the holder reversed the direction of the circuit is reversed. Thus, a draft is created which keeps the cigarette lighted. I find that without these openings near the butt end of the cigarette, i. e., the end opposite the lighted end that the cigarette will remain lighted a very much shorter period. In short, the two sets of air openings are essential to provide the necessary circulation to maintain the cigarette in lighted condition for periods of time as herein set forth. One set of openings should be located in the end of the encasing member at or slightly beyond the lighted end of the cigarette, while the other set of openings should be located in spaced relation longitudinally of the casing member, and preferably near the opposite end of the cigarette.

When it is desired to discontinue smoking the cigarette, and place the holder in a pocket, the openings may be closed by revolving the parts to bring the passageways and openings out of registration so that said openings are thus closed to the outside. Hence, the cutting off of air promptly causes the cigarette to be extinguished and the ashes are prevented from escape so that the holder may be carried in the pocket, and the cigarette subsequently relighted if desired.

When it is desired to discontinue smoking the cigarette and not close the openings, the holder may be disposed in a horizontal position whereupon the lighted partially smoked cigarette will become extinguished in a matter of seconds.

The modified forms illustrate various types of construction which provide more simple methods of manufacture. The mode of operation of the modified forms is substantially that of the preferred form set forth above. Some of the parts are shown integral as in Fig. 8, where the mouthpiece 49 is the holder and mounting member. Also the enveloping casing member 50 has the cap or front end portion formed integrally.

Obviously, changes may be made in some of the forms, dimensions and arrangements of the parts of my invention without departing from the principle thereof, the above setting forth only preferred forms of embodiment.

I claim:

1. A cigarette holder comprising a mouthpiece; a cigarette holder member; a cigarette enveloping casing mounting member disposed upon said holder member and having circumferentially spaced openings and offset connecting grooves, as longitudinally extending grooves connected with said openings; an enveloping casing member disposed on and mounted for angular movement as respects the said mounting member and having at one end portion, circumferentially spaced openings moveable into and out of registration with said grooves in said mounting member upon angular movement of said casing member relatively as respects said mounting member, whereby openable and closable air passageways may be formed through said openings and said grooves and light may be masked; and a cap member for said casing member.
2. A cigarette holder comprising a mouthpiece; a cigarette holder member; a cigarette enveloping casing mounting member disposed upon said holder member and having circumferentially spaced openings and offset connecting grooves, as longitudinally extending grooves connected with said openings; an enveloping casing member disposed on and mounted for angular movement as respects the said mounting member and having at one end portion, circumferentially spaced openings moveable into and out of registration with said grooves in said mounting member upon angular movement of said casing member relatively as respects said mounting member, and having at the other end portion circumferentially spaced openings, whereby air passageways may be formed through said openings at the said one end portion of the casing member, the said grooves, and the said openings in the mounting member and light may be masked; and a cap member disposed on and mounted for angular movement as respects said casing member and having openings and offset connecting grooves, as longitudinally extending grooves, moveable into and out of registration with the said openings in said other end portion of said casing member, whereby openable and closable air passageways may be formed through said openings at the said other end portion of the casing member, the said second mentioned grooves, and the said openings in the cap member and light may be masked.
3. A cigarette holder comprising a mouthpiece; a cigarette holder member; a cigarette enveloping casing mounting member disposed upon said holder member; an enveloping casing member having one end portion disposed on said mounting member and having at its other end portion circumferentially spaced openings; and a cap member disposed on and mounted for angular movement as respects said cap member and having openings and offset connecting grooves, as longitudinally extending grooves movable into and out of registration with the said openings in said other end portion of said casing member, whereby openable and closable air passageways may be formed through said openings at the said other end portion of the casing member, the said grooves, and the said openings in the cap member and light may be masked.
4. An enclosed light masking cigarette holder comprising an enveloping casing member having a match inserting opening adjacent the location where a cigarette is to be lighted; a punctured elastic covering for said opening; and a fixedly mounted match scratching element registering

with said match inserting opening, whereby a match may be lighted in said casing member, without external light, and the fire on the match upon withdrawal may be extinguished by said elastic covering.

5. An enclosed light masking cigarette holder comprising an enveloping casing member having a match inserting opening adjacent the location where a cigarette is to be lighted; a punctured

elastic covering for said opening; and a fixedly mounted match scratching element having an abrupt match engaging corner registering with said match inserting opening, whereby a match may be lighted in said casing member, without external light, and the fire on the match upon withdrawal may be extinguished by said elastic covering.

WILLIE A. OLSON.
